UNITED STATES PATENT OFFICE.

ANDREW M. HUNT AND THOMAS MIRK, OF SAN FRANCISCO, CALIFORNIA.

HYDROCARBON-BURNER.

SPECIFICATION forming part of Letters Patent No. 768,368, dated August 23, 1904.

Application filed April 1, 1903. Serial No. 150,522. (No model.)

To all whom it may concern:

Be it known that we, ANDREW M. HUNT and THOMAS MIRK, citizens of the United States, residing in the city and county of San Francisco, State of California, have invented certain new and useful Improvements in Hydrocarbon-Burners; and we do hereby declare the following to be a full, clear, and exact description of the same.

10 Practical operation of burners employing a combustion-chamber into which the hydrocarbon is injected has demonstrated that by reason of the intensity of the heat generated therein the roof or cover-wall of the said combustion-chamber quickly burns out and renders the burner inefficient and short-lived. Especially is such the case with the construction of burner set forth and described in our joint application, Serial No. 136,128, for an 15 improved hydrocarbon-burner, filed in the United States Patent Office on the 22d day of December, 1902.

The object of the present invention is to overcome such defect in this class of burners, 20 so as to prolong the life thereof, which we have ascertained capable of being successfully accomplished by introducing above and in contact with the roof or top wall of the combustion-chamber a current of air sufficient to 25 maintain the top wall or roof at a lower temperature than the internal temperature of the said combustion-chamber.

To comprehend the invention, reference should be had to the accompanying sheet of drawings; wherein—

30 Figure 1 is a longitudinal sectional view of the burner. Fig. 2 is a vertical sectional end view on line *xx*, Fig. 1 of the drawings. Fig. 3 is a similar view taken on line *yy*. Fig. 4 is a modification of the burner. Fig. 5 is a vertical sectional end view taken on line *vv*, Fig. 4 of the drawings; and Fig. 6 is a similar view taken on line *ww*.

The numeral 1 indicates a longitudinal flue, 35 the interior of which serves as a combustion-chamber 2. This flue at its rear end is closed, and in the side walls thereof is provided the outlet-openings 3. The hydrocarbon is injected into the forward end of the chamber 2 by means of the nozzle 4, the discharge end

of which extends within the open end of the flue 1.

Below the flue 1 is arranged an air-flue 5, which communicates at its rear end by passage-way 6 with an upper flue 7. The flue 7 is arranged immediately above the roof or top wall 8 of the combustion-chamber 2, so that the air fed into flue 5 is drawn over the upper surface of the top or roof wall 8 in order to maintain the same at a somewhat-reduced temperature or at a temperature considerably below that within the combustion-chamber. The forward end of the flue 7 is closed, and the said flue communicates with the interior of the combustion-chamber by means of the passage-way 9, formed through the roof or top wall 8.

Under this construction a body of comparatively cool air is maintained circulating over the surface of the top wall or roof 8 of the combustion-chamber.

We have ascertained that under the above construction the life of the burner, so far as relates to the utilization of the described combustion-chamber, is considerably prolonged.

It is obvious that in lieu of the means of introducing the fresh air over the roof or top wall of the combustion-chamber 2 (set forth in Figs. 1, 2, and 3 of the drawings) that a single flue 10 may be employed, Figs. 4, 5, 8c and 6 of the drawings. In such case the flue, like flue 7, is arranged immediately above the roof or top wall 8 of the combustion-chamber, said flue taking air directly into its forward open end. Under this arrangement the air is not conveyed below the flue 1. The gases escape from the burner through the lateral outlets or side openings 3.

Having thus described the invention, what is claimed as new, and desired to be protected by Letters Patent, is—

In a hydrocarbon-furnace, the combination of an outer wall, the top, bottom and one end of which being continuous and uninterrupted, and the opposite end having a fresh-air inlet at its lowermost portion, and a combustion-chamber within said outer wall comprising a bottom section integral with the side walls of the furnace at a point above said opening, an end section, a top section terminating in

advance of the top of the outer wall for forming an opening communicating with the combustion-chamber, the space between the combustion-chamber and outer wall being continuous and uninterrupted, and a nozzle for hydrocarbon passing through the outer wall to a point immediately below said last-mentioned opening.

In witness whereof we have hereunto set our hands.

ANDREW M. HUNT.
THOMAS MIRK.
